THOMAS L. LEE, OF ROCHESTER, NEW YORK, ASSIGNOR TO NORTH EAST ELECTRIC COMPANY, OF ROCHESTER, NEW YORK, A CORPORATION OF NEW YORK.

IGNITION COIL.

Application filed February 3, 1926. Serial No. 85,809.

This invention relates to ignition coils such as are used in connection with internal combustion engines.

In the design of an ignition coil, one of the problems to be met is the provision for escape of heat generated in the primary winding, particularly where this winding is enclosed by insulating material and a secondary winding, in the usual manner. While the amount of heat may not be excessive during normal operation of the coil, it sometimes happens that the primary circuit is left constantly closed, through failure of the operator to open the ignition switch when operation of the engine is stopped and in such a case there is danger of overheating and injuring the coil, unless effective means are provided for dissipating the heat.

In the manufacture of ignition coils it is common to use a magnetic core of laminated construction, wind the primary winding upon a stiff sleeve or tube of paper, or other insulating material, and afterwards introduce the core into this sleeve. In such a construction, while a certain amount of heat from the winding escapes to the core, and is carried away by the latter, the sleeve upon which the winding is mounted constitutes a serious barrier to the transmission of heat.

The object of the present invention is to avoid the heat insulation resulting from the construction just described, and to provide a construction in which the heat may be much more effectively transferred from the primary winding to the magnetic core. To this end, it is proposed to substitute a metal sleeve for the sleeve of insulating material commonly used, this metal sleeve being in direct heat conducting engagement with the

core. In so doing, it is necessary to make provision against the formation of circuits in which eddy currents may be generated, and the invention resides particularly in the form and construction of the metal sleeve by which it is engaged non-rotatively with the coil, and is at the same time so divided and insulated as to provide against the production of such circuits.

In the accompanying drawings, Fig. 1 is a vertical section of a complete ignition coil embodying the present invention. Fig. 2 is a plan view of the core, with the primary winding and the interposed metal sleeve shown partly in section. Figs. 3 and 4 are sectional views, on an enlarged scale, on the

lines 3-3 and 4-4 in Fig. 2; and Fig. 5 is a plan-view of one of the members of the metal sleeve, seen at its inner side.

The invention is shown as embodied in an ignition coil having a primary winding 10 and a secondary winding 11, surrounding the straight central member of a laminated core 12. These parts are embraced between upper and lower casing-members 13 and 14.

The core is divided into two halves, for convenience in assembling it with the previously formed windings. The central member 15 of the core is of rectangular cross-section, and the laminæ in it are secured together by rivets 16.

The metal sleeve, in the use of which the present invention particularly resides, comprises two similar members 17, stamped into the form shown, in cross-section, in Figs. 3 and 4. Preparatory to the formation of the

primary winding, sheets of thin, flexible insulating material, such as varnished silk, are laid over the outer surfaces of these members, and one edge 18 of each insulating sheet is interposed between two of the adjacent edges of the sleeve-members, so as to provide a longitudinal separation or insulated joint. The sleeve-members are held in this position while the primary winding is wound directly upon the thin insulating material, the metal sleeve thus serving as a support for the winding during its formation. The secondary winding, which has previously been formed in any convenient manner, is then placed around the primary winding, and the two halves of the core are then brought together, with the divided central member 15 introduced into the metal sleeve.

The form of the sleeve is preferably such that it has inner reentrant angles which directly engage the salient angles of the rectangular core, thus providing for efficient heat conduction at these points. Between the angles mentioned, the sleeve is curved away from the core, particularly at the parts opposite edges of the laminæ. In case the core laminæ are riveted together, as in the illustrated construction, the sleeve is also preferably curved away to afford space for the heads of the rivets, as shown in the drawings. Even at the parts where the sleeve is not in engagement with the core, however, heat transference by radiation and convection may readily take place; and since

only a minimum thickness of insulating material is interposed between the primary winding and the core, it has been found that the escape of heat from the winding is greatly improved by the substitution of the metal sleeve for the usual rigid tube of non-metallic material. Where the core is riveted, it is important that two opposite insulated joints be provided in the metal sleeve, these joints being located between the opposite ends of the rivets, since otherwise a circuit for eddy currents, passing in part through the rivets, would be produced. The thickness of the laminated core inevitably varies somewhat in manufacture, and allowance must be made for this in the inside dimensions of the metal sleeve. To provide for a secure non-rotative engagement between the parts under these conditions, lugs 19 are formed near the ends of the sleeve-members, by pressing the sheet-metal inwardly at these points, so that a secure engagement results, even though the fit between the top and bottom of the core and the sleeve, respectively, be somewhat loose.

The sleeve is shown in the drawings as being out of engagement with the heads of the rivets, but this is not essential provided the sleeve has two longitudinal insulated joints located as shown. The cross-section of the sleeve, as illustrated, shows smoothly curved portions extending from angle to angle. This curved form facilitates the winding of the primary wire upon the sleeve, but is not essential to the embodiment of the invention. The sleeve may be made of any convenient metal, since even metals having relatively low heat-conductivity are greatly superior, in this respect, to any of the non-metallic materials commonly used as supports for the primary winding.

The invention claimed is:

1. In an ignition coil, the combination, with a laminated magnetic core of polygonal cross-section, and a primary winding surrounding the core, of a metal sleeve interposed between the core and the winding, said sleeve being formed for non-rotative engagement with the core at the salient angles of the core, and having at least one longi-

tudinal insulated joint located between the points of engagement of the sleeve with the opposite outermost laminæ of the core.

2. In an ignition coil, the combination, with a magnetic core comprising laminæ and rivets securing the laminæ together, and with a primary winding surrounding the core, of a metal sleeve interposed between the core and the winding and formed to engage the core non-rotatively at opposite salient parts of the core, said sleeve having two opposite longitudinal insulated divisions each located between opposite ends of the said rivets.

3. In an ignition coil, the combination, with a laminated magnetic core of rectangular cross-section, and a primary winding surrounding the core, of a metal sleeve interposed between the winding and the core and formed with inner angles engaging the angle of the core, the sleeve being curved away from the edges of all but the outermost laminæ of the core and having a longitudinal insulated division between its points of engagement with the two outermost laminæ.

4. In an ignition coil, the combination, with a laminated magnetic core of rectangular cross-section, and a primary winding surrounding the core, of a metal sleeve interposed between the winding and the core, engaging the core at its angles and curved away from the core between said angles, the sleeve being provided with inwardly pressed lugs engaging the core adjacent said angles, and comprising two members longitudinally separated and insulated from each other.

5. In an ignition coil, the combination, with a laminated magnetic core and a primary winding surrounding the core, of a metal sleeve interposed between the winding and the core and engaging the core at a plurality of opposite points, said sleeve comprising two similar longitudinally divided members; and thin flexible insulating material surrounding the sleeve and extending between the adjacent edges of the sleeve-members.

THOMAS L. LEE.
